Primary Examiner — Bridget L Eland(74) *Attorney, Agent, or Firm* — Fredrikson & Byron, P.A.(57) **CLAIM**

The ornamental design for a lesser metatarsal cut guide, as shown and described.

DESCRIPTION

FIG. 1 is a perspective view of our new design for a lesser metatarsal cut guide;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines immediately adjacent the shaded areas represent the bounds of the claimed design while all other broken lines are directed to environment and are for illustrative purposes only; the broken lines form no part of the claimed design.
